WINDOW SCREEN

John M. Lapina, Brooklyn, N. Y.

Application July 27, 1943, Serial No. 496,289

6 Claims. (Cl. 160—84)

This invention relates to window screens.

It is the primary object of this invention to provide a collapsible and removable window screen comprising an accordion pleated sheet of specially prepared paper secured to a plurality of supporting bars of wood which are held in spaced apart relation by a pair of pivoted wood links, so arranged relative to each other and to the supporting bars, that when moved together the screen will be collapsed and when separated the screen will be extended for use, the paper making up the screen being suitably perforated in the pleats thereof.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein—

Figure 1 shows the paper screen placed in position in a window frame opening as viewed from the inside of the room.

Figure 2 is an elevational view of the paper screen as extended ready for use.

Figure 3 is an end elevational view of the extended screen of Figure 2.

Figure 4 is an elevational view of the screen showing the same collapsed.

Figure 5 is an end elevational view of the collapsed screen of Figure 4.

Referring to the drawing in detail, 5 denotes a conventional window frame including upper and lower window sections which may be raised or lowered in the manner well known. Placed in position between the raised lower window section and the sill of the window frame is a collapsible paper screen 10 embodying the novel features of the invention, the screen being viewed from the inside of the room.

The screen 10 comprises a bottom support bar 11, an intermediate support bar 12, and a top support bar 13 which may be formed of any suitable material, preferably wood. The bars are rectangular in cross-section and of uniform width, thickness and length; the length being such as to extend between the opposed sides of the window frame 5, for placement preferably in the window channels thereof.

Interconnecting the support bars 11, 12 and 13 are connecting links 15 and 16 which may be of any suitable material, preferably wood. The links 15 and 16 are each pivotally secured at their lower ends to the lower support bar 11 at points adjacent the ends thereof, by means of pivot pins 17 and 18, respectively. The intermediate support bar 12 and the top support bar 13 are each provided with a pair of longitudinally extending slots 20 and 21, respectively, arranged symmetrically on each side of the vertical center of said bars, with the slots 20 of a less length than the slots 21 and with the outer ends of said slots in substantially vertically aligned relation. Guide pins 24 and 25 are pivotally connected to the links 15 and 16, for sliding movement, respectively, in the slots 20 and 21. Preferably the pins 24 and 25, should be of such dimensions as to have a frictional sliding engagement in their associated slots, whereby for any position of adjustment of the links the same will be held therein relative to the support bars 12 and 13. If desired the pins 24 and 25 may have threaded ends to receive wind nuts thereon for clamping the links to the support bars in adjusted position. The length of the links 14 and 15 and slots 20 and 21 are so co-related that the support bars 11, 12 and 13 will contact each other when the links are drawn together to their maximum extent, this being the fully collapsed position of the screen 10. With the links 14 and 15 separated their maximum extent, the screen will be fully extended.

Appropriately secured as by tacking, gluing or cementing (not shown) to the support bars 11, 12 and 13 on the side thereof opposite the links 14 and 15 is a paper screen 30 folded into horizontal rows of pleats 31, 32 so as to provide an accordion effect. The paper screen 30 is made of a suitable, tough, water-proof paper of a requisite degree of stiffness and strength suitable for the purpose intended. Provided in the pleats 31 and 32 are perforations 33 of any desired shape or size. The intermediate support bar 12 is secured to the paper screen 30 along the horizontal center line thereof so as to be always equally spaced from the lower and top support bars.

When placed in a window opening the screen 10 is positioned with the paper screen 30 facing the outside. The links 14 and 15 further function to prevent inward bending or billowing of the paper screen 30 in the event the wind blows 55 into the room.

Having thus described the invention, what is claimed is:

1. A collapsible and removable window screen comprising a plurality of support bars, a plurality of links pivotally connected to one of said support bars and having a sliding connection with the remainder of said support bars, and a horizontally pleated collapsible paper screen attached to said support bars, in the collapsed position of the screen said support bars engaging each other and in the extended position of said screen said support bars being disposed and held by said links in horizontally spaced relation.

2. A collapsible and removable window screen comprising a plurality of support bars, a plurality of links pivotally connected to the lowermost one of said support bars and having a sliding connection with the remainder of said support bars, and a horizontally pleated collapsible paper screen attached to said support bars, in the collapsed position of the screen said support bars engaging each other and in the extended position of said screen said support bars being disposed and held by said links in horizontally spaced relation, and a row of perforations formed in each of said pleats.

3. A collapsible and removable window screen comprising a plurality of support bars of equal length, a plurality of links of equal length pivotally connected to the lowermost one of said support bars and having a sliding friction connection with the remainder of said support bars, and a horizontally pleated collapsible paper screen attached to said support bars, in the collapsed position of the screen said support bars engaging each other and in the extended adjusted position of said screen said support bars being disposed and held by said links in horizontally spaced relation, and a row of perforations formed in each of said pleats.

4. A collapsible and removable window screen comprising a plurality of support bars of equal length, a plurality of links of equal length pivotally connected to the lowermost one of said support bars and having a sliding friction connection with the remainder of said support bars,

and a horizontally pleated collapsible paper screen attached to said support bars on the side thereof opposite that engaged by the links, in the collapsed position of the screen said support bars engaging each other and in the extended adjusted position of said screen said support bars being disposed and held by said links in horizontally spaced relation, and a row of perforations formed in each of said pleats.

5. A collapsible and removable window screen comprising a lower, an intermediate and a top support bar, a pair of links each pivotally connected to the lower support bar at points adjacent the ends thereof, a pair of longitudinally spaced slots formed in each of the other of said support bars, guide means on said links having frictional sliding engagement in said slots, and a horizontally pleated perforated collapsible paper screen attached to said support bars, in the collapsed position of the screen said support bars engaging each other with the links inclined towards each other and in the extended adjusted position of said screen said support bars being disposed and held by said links in horizontally spaced relation with said links approaching a substantially vertical position.

6. A collapsible and removable window screen comprising a lower, an intermediate and a top support bar, a pair of links each pivotally connected to the lower support bar at points adjacent the ends thereof, a pair of longitudinally spaced slots formed in each of the other of said support bars, guide means on said links having frictional sliding engagement in said slots, and a horizontally pleated perforated collapsible paper screen attached to said support bars on the side thereof opposite that engaged by the links, in the collapsed position of the screen said support bars engaging each other with the links inclined towards each other and in the extended adjusted position of said screen said support bars being disposed and held by said links in horizontally spaced relation with said links approaching a substantially vertical position, said perforations being formed in each of said pleats.

JOHN M. LAPINA.
